UNITED STATES PATENT OFFICE.

MILTON JACKSON, OF PHILADELPHIA, PENNSYLVANIA, ASSIGNOR TO THE
D. K. MILLER LOCK COMPANY, OF SAME PLACE.

COMBINATION-FINDER FOR LOCKS.

SPECIFICATION forming part of Letters Patent No. 427,421, dated May 6, 1890.

Application filed August 29, 1889. Serial No. 322,317. (No model.)

To all whom it may concern:

Be it known that I, MILTON JACKSON, a citizen of the United States, and a resident of Philadelphia, Pennsylvania, have invented an
5 Improved Combination-Finder for Locks, of which the following is a specification.

My invention consists of an improved device for determining the combination to which the permutation wheels or disks of a combination-lock are set, the object of the invention being to provide for accurately indicating the combination on the graduated face of the lock without forming in the lock-case an opening of as great a width as the width of
10 the notches in the permutation-disks. This object I attain in the manner hereinafter set forth, reference being had to the accompanying drawings, in which—

Figure 1 is a sectional view of a combination-lock, illustrating the permutation disks or tumblers and the combination-finder in elevation. Fig. 2 is a rear view of part of the lock; and Fig. 3 is a perspective view, on a larger scale, of the permutation-disks and combination-finder.

It is a common practice to provide the inner casing of a combination-lock with an opening in line with the notched faces of the permutation tumblers or disks when they are in position for the entrance of the dog on the bolt, so that their position may be noted, or a pin may be passed through said opening for engagement with the notches of the successive disks as they are turned to bring said notches in line with the pin, the combination to which the lock is set being determined by inspection of the numbers on the knob and dial as the notches of successive tumblers are brought into line. If the opening is large enough to receive a pin of the full width of the notches, however, dust and dirt can freely enter the lock-casing, so as to clog or otherwise interfere with the delicate mechanism of the lock, and the tumblers and disks are, moreover, exposed to an unwarranted extent, while if, on

the other hand, the pin and its openings are small there is more or less lost motion of the permutation tumblers or disks, due to the fact that the pin does not fill the notches in the same; hence the indications given by the 50 graduated knob and dial of the lock are not accurate.

In carrying out my invention, therefore, I use a double pin A, the two prongs *a* of which are at a distance apart equal to the width of 55 the notches in the tumblers or disks *d* of the lock, each prong of the pin, however, being very small in diameter, and the opening *b* in the lock-case for the passage of the prongs of the pin being of correspondingly-small diameter, as shown in Fig. 2, so that they are not subject to the objections attending the use of a single large opening, while, on the other hand, the prongs of the pin fill the notches in the disks or tumblers, and there is not that 60 want of accuracy in the indications on the face of the lock which attends the use of a single small pin.

Having thus described my invention, I claim and desire to secure by Letters Patent— 70

1. The within-described combination-finder for combination-locks, the same consisting of a double pin, the prongs of which are spaced to accord with the width of the notches in the permutation tumblers or disks of the lock, 75 substantially as specified.

2. The combination of the double pin with the lock having a casing with spaced openings for the passage of the prongs of the pin, the latter being spaced to accord with the width 80 of the notches in the tumblers or disks of the lock, substantially as specified.

In testimony whereof I have signed my name to this specification in the presence of two subscribing witnesses.

MILTON JACKSON.
